UNITED STATES PATENT OFFICE.

ABIJAH E. HAMPTON, OF PITTSTOWN, AND CHARLES S. MARSHALL, OF BAPTISTOWN,
NEW JERSEY.

MUFFLER.

Application filed April 27, 1926. Serial No. 104,893.

This invention relates to mufflers for silencing the exhaust noise of internal combustion engines.

The present day muffler, as it is well known, retains a large volume of gases therein. This is due to its construction which provides large spaces through which the exhaust gases pass during the silencing action. Should the ignition system fail to explode one or more charges of fresh gas in the engine cylinders, these charges will be expelled into the muffler and the muffler will be filled with the fresh gas. When the ignition system functions again, the hot exploded gases, expelled from the cylinders into the muffler, ignite the fresh gases therein and explode them with a violent force, causing serious damage to the muffler. It oftentimes happens that only the interior of the muffler is damaged. This is not readily detected and usually obstructs the passage for the gases, thereby causing high back pressure on the engine. As a result, the engine, though it be in excellent working condition, fails to produce the usual power and this causes much trouble and inconvenience.

The objects of our invention are to provide a muffler which will, to a large extent, overcome the danger of damage to the muffler; which is highly efficient in its silencing action, and which, when the engine runs at slow speed, will have little silencing effect on the exhaust gases so as to enable one to hear and detect any irregularity in the order of firing of the engine cylinders.

These objects, and other advantageous ends which will be described hereinafter, we attain in the following manner, reference being had to the accompanying drawings in which—

Figure 1 is a side elevation of a muffler constructed in accordance with our invention.

Figure 2 an end view of the muffler shown in Figure 1 looking from the left.

Figure 3 a like view of the muffler looking from the right of Figure 1.

Figure 4 a central longitudinal sectional view taken on line 4—4 of Figure 3,

Figure 5 a transverse sectional view taken on line 5—5 of Figure 4, and

Figure 6 a like view taken on line 6—6 of Figure 4.

Referring to the drawings, 1 indicates an

outer shell, 2 an inner shell disposed concentrically thereto, 3 a head on the rear end of the shells for keeping them properly spaced, 4 a head on the front end of the inner shell, 5 a head on the front end of the outer shell, 60 heads 4 and 5 being separate parts to facilitate assembling, 6 tie bolts passing through the heads and within the shells for fastening the heads to the shells, 7 an exhaust pipe of an internal combustion engine connected 65 with the front head, and 8 a manifold connected with the exhaust pipe, which changes pulsating exhaust gases coming from the exhaust pipe to a continuous stream and thus effects a silencing action on the exhaust 70 noises.

The manifold consists of a unit 9, for convenience called "discharge unit", and a series of units 10 hereinafter called "suction units". The discharge unit 9 is provided 75 with a discharge conduit 11 spaced from and surrounding a central conduit 12. The exhaust gases pass through the space between conduits 11 and 12, and issue from the discharge unit through outlet 13 into the inner 80 shell 2, from which they are sucked by the suction units 10.

The suction units, which are four in number, each consists of a suction conduit 14 spaced from and surrounding a central conduit 15, aligned with central conduit 12, and an inlet 16 communicating with the suction conduit 14. The exhaust gases as they are sucked from shell 2 enter inlet 16 and pass through the space between suction conduit 90 14 and central conduit 15. We have shown four suction units 10 but any desired number may be used to meet different requirements. We preferably provide a pressure equalizing chamber 17 between the discharge unit 9 and the adjacent suction unit 10 and also between the suction units 10. These chambers act to store the high pressure pulsating volumes of exhaust gases, and release them at a less and more uniform pressure to the adjacent suction unit 10. The manifold 8 is mounted in the rear head 3 and is fastened to the front head 5 by a bolt 18 passing through a boss 19 on head 5. This bolt also passes through exhaust pipe 7 and fastens it to the 105 muffler.

The inner shell has an opening 20 adjacent the rear end thereof to allow excess exhaust gases discharged therein to pass to the outer shell. The gases then pass out from the 110

outer shell through an opening 21 in a pipe 22 and then pass through this pipe out of the muffler. Pipe 22 also serves to connect the heads to the shells by nuts 23 similar to tie bolts 6. A bracket 24 is attached to the rear head 3 for securing the muffler to the vehicle.

In operation the exhaust gases coming from pipe 7 in successive pulsating volumes pass partly through central conduit 12 and 10 the remainder pass through the space between said conduit and the discharge conduit 11. The gases passing through conduit 12 enter the first pressure equalizing chamber 17 and then pass through the central conduit 15 of the suction unit. The gases issue from this conduit 15 in a jet within suction conduit 14 and create a region of low pressure due to the high velocity of the gases. The gases discharged through outlet 20 13 into the inner shell rush through inlet 16 into the region of low pressure in suction conduit 14 as indicated by the arrows. The gases then pass into the second pressure equalizing chamber 17 and from there into 25 the central conduit 15 of the next suction unit 10. The action of the gases through this next unit and the succeeding ones is similar to the action just described in the preceding unit 10. The gases are thusly discharged 30 from the discharge unit 9, and sucked through outlets 16 into each of the suction units 10 to the region of low pressure in the central conduit 14. This action of the gases changes the successive gas pulsations coming 35 from the exhaust pipe 7, to a continuous stream which issues quietly from the flared outlet end 25 of the manifold. The equalizing chambers 17 aid in changing these successive gas pulsations of non-uniform velocities and pressures, to a continuous gas stream 40 of practically uniform velocity and pressure. When an excessive amount of gases comes from discharge pipe 7, they may pass out from the inner shell through the opening 20 45 to the outer shell and then through the opening 21 into the pipe 22 and out of the muffler as indicated by the arrows.

When the engine is operated at slow speed with the vehicle idle to ascertain the regularity of the order of firing of the cylinders, the gases coming from discharge pipe 7 are of such slow speed that little suction is created in the suction units 10 and consequently little silencing action is produced on 55 the gases, thus enabling one to hear and detect any irregularity in the order of firing of the cylinders.

The muffler above described is practically free of the danger of harmful explosions 60 caused by the misfiring of the engine cylinders, because little or practically none of the fresh gas remains in the inner shell of the muffler, owing to the constant suction of the suction units 10.

65 While we have described our invention as

taking a particular form, it will be understood that the various parts may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:—

1. A muffler including a casing and a manifold passing through the casing; the manifold having a longitudinal central passage therethrough, a discharge conduit communicating with the casing, a series of suction conduits communicating with the casing with the inner ends of said suction conduits surrounding but spaced from walls of the central passage, and an expansion chamber formed in the central passage between each two suction conduits. 80

2. A muffler including a casing and a manifold passing through the casing, said manifold having a discharge conduit communicating with the casing; a central conduit within and spaced from the discharge conduit; a second central conduit communicating with the first mentioned central conduit, and a suction conduit surrounding the last mentioned central conduit and spaced therefrom, whereby gases passing through the manifold will partly discharge through the discharge conduit into the casing and partly pass through the central conduits to create a suction at the 100 suction conduit for drawing the gases from the casing back into said conduit. 90

3. A muffler including an inner shell, an outer shell surrounding the inner shell and communicating therewith and with the outer 105 air, and a manifold passing through the inner shell; the manifold having a longitudinal central passage therethrough, a discharge conduit communicating with the inner shell, and a series of suction conduits communicating with the inner shell with the inner ends of said suction conduits surrounding but spaced from walls of the central passage. 110

4. A muffler including an inner shell; an 115 outer shell surrounding the inner shell and communicating therewith, and a manifold passing through the inner shell, said manifold having a conduit for discharging gases into the inner shell, suction conduits for 120 drawing the gases from the inner shell back into said manifold, and a conduit leading from the outer shell to the outer air. 125

5. A muffler including an open ended inner shell having an opening in its wall; an open ended outer shell surrounding the inner shell; a head mounted on the rear end of the shells; a head mounted on the front end of the inner shell; a head mounted on the front end of the outer shell; means passing through 130

the heads and within the shells for fastening the heads to the shells; a manifold passing within the inner shell; said manifold having means for discharging gases into the inner shell, and means for causing suction for drawing the gases from the inner shell back into said manifold, and a conduit se- cured to the heads and passing within the outer shell for discharging gases therefrom. In testimony whereof we have signed our ¹⁰ names to this specification.
